ATTORNEY

INVENTOR

UNITED STATES PATENT OFFICE.

KASIMIR W. NAJDER, OF DETROIT, MICHIGAN, ASSIGNOR OF ONE-FOURTH TO ISAAC S. GELLERT, OF DETROIT, MICHIGAN.

SLEEVE-VALVE MECHANISM.

Application filed November 3, 1922. Serial No. 598,772.

To all whom it may concern:

Be it known that I, KASIMIR W. NAJDER, a citizen of the United States, and residing at Detroit, in the county of Wayne and State 5 of Michigan, have invented a new and Improved Sleeve-Valve Mechanism, of which the following is a specification.

This invention relates to the valve construction of internal combustion engines, particularly to that class of valves which are 10 in the form of sleeves and constitute the linings of the engine cylinders, and its object is to provide a novel type of valve operating mechanism which will cause every point on 15 the valve to travel a triangular path.

This invention consists in a cylinder having intake and exhaust ports, a sleeve valve rotatable and slideable in said cylinder and having a port adapted to register with the 20 intake and exhaust ports alternately, and a valve operating mechanism adapted to cause, the individual parts of the sleeve valve to travel a triangular path.

It also consists in the details of construction illustrated in the accompanying drawing and particularly pointed out in the claims.

In the drawing, Fig. 1 is a vertical section of an engine embodying my improved 30 valve mechanism. Fig. 2 is a detail on a larger scale of the gearing for actuating the valve. Figs. 3 and 4 are end and side elevations of the cross head for actuating the valve. Fig. 5 is an elevation of the cross 35 head guide and of the cross head therein. Figs. 6 and 7 are details of gearing therefor. Fig. 8 is a diagram showing the relative movements of the parts. Fig. 9 is a detail of a modified construction embodying 40 a series of sets of ports.

Similar reference characters refer to like parts throughout the several views.

The engine shown in the drawing embodies a crank case 1, crank shaft 2 with 45 crank pin 3, connecting rod 4, cylinder 5 with its water jacket 6, intake passage 7 and exhaust passage 8, piston 9, cylinder head 10 with its spark plug 11 and packing rings 12 and 13 and the sleeve valve 14. Means are 50 provided to cause the valve to move circumferentially and longitudinally in opposite directions and then circumferentially alone so that each portion of the valve travels a triangular path.

55 A shaft 16 is driven by the main shaft 2

at one-half the speed of the main shaft in any desired manner and in either direction gears 17, 18 and 19 being indicated. On this shaft 16 is a screw-gear 20 meshing with a similar gear 21 on the stub shaft 22 which 60 has a cross blade 23 at one end extending into and slideable in the groove 24 in the cross-head 25. This cross-head is mounted in a guide 26 having a substantially triangular recess 27 to receive the cross-head. 65 A pin 28 extends from this cross-head and is slideable in a ball 29 and a sleeve 30 attached thereto. The ball is mounted in a socket 32 attached to the valve 14, preferably 70 to the lower end thereof.

The design of the recess 27 in the guide 26 and of the cross-head 25 are such that the rotation of the shaft 22 will cause the axis of the pin 28 to travel a triangular path 75 which is also substantially the path of the center of the ball 29 and of every point on the valve 14.

The cylinder is formed with an intake port 34 and exhaust port 35 connecting to the passages 7 and 8 respectively and the 80 valve 14 is formed with a port 36. The diagram Fig. 8 indicates the relative positions of these ports during the operation of the engine, the dotted rectangles A, B, C and D indicating the positions of the port 36 in the valve relative to the ports 34 and 35 at the times the piston 9 is at the end of the scavenging, intake, compression and explosion or working strokes respectively. 85 This set of ports may be repeated around the cylinder in which case the passages 7 and 8 may both extend entirely around the cylinder, portions thereof being displaced longitudinally of the cylinder to connect to the several ports 34 and 35 which could 90 then be in the same transverse plane, as indicated in Fig. 9. This permits the individual ports to be made quite small and the necessary movement of the valve to be 95 reduced to a minimum.

The details of construction and the proportions of the parts may all be changed by those skilled in the art without departing from the spirit of my invention as set forth in the following claims.

I claim:

1. In an engine, the combination of a cylinder having intake and exhaust ports, a sleeve valve in the cylinder and having a 110 port, a piston slideable within said valve and

- means to cause the valve to turn without longitudinal movement to cause the valve port to register with the cylinder ports alternately and then turn back the same distance while moving back and forth longitudinally.
2. In an engine, the combination of a cylinder having intake and exhaust ports, a sleeve valve in the cylinder and having a port adapted to register with the cylinder ports alternately, a piston slideable within said valve and means to cause each point of the valve to travel a substantially triangular path.
3. In an engine, the combination of a cylinder having intake and exhaust ports, a sleeve valve in the cylinder having a port adapted to register with the cylinder ports alternately, a valve shaft driven by the engine at one-half crank shaft speed, a guide, a cross head mounted therein and having a crank pin caused to move in a triangular path by said guide, means to connect the valve shaft to said cross head, and means connecting the crank pin to the valve.
4. In an engine, the combination of a cylinder having intake and exhaust ports, a sleeve valve in the cylinder having a port adapted to register with the cylinder ports alternately, a valve shaft driven by the engine at one-half crank shaft speed, a guide, a cross head mounted therein and having a crank pin caused to move in a triangular path by said guide, means to connect the valve shaft to said cross head, and means connecting the crank pin to the valve.
5. In an internal combustion engine, a cylinder having inlet and exhaust ports, a cylindrical valve slideable within the cylinder having suitable ports, a piston slideable within the valve and means to operate said valve to give it a combined slideable and rotatable movement causing the valve ports to travel in a substantially triangular path.
6. In a four-cycle internal combustion engine, a cylinder having inlet and exhaust ports, a cylindrical valve arranged substantially co-axial with the cylinder and having a combined slideable and rotatable movement causing the valve port to travel in a substantially triangular path, one side of which is in a plane perpendicular to the axis of the cylinder, a piston slideable within said valve and means to actuate the valve.
7. In an engine, the combination of a cylinder having inlet and exhaust ports, a cylindrical valve mounted within the cylinder, and means for imparting to said valve a substantially triangular movement, said inlet and exhaust ports of the cylinder being in a plane which is at right angles to the axis of the cylinder, one side of which is in a plane perpendicular to the axis of the cylinder to control the inlet and exhaust.

KASIMIR W. NAJDER.
